(57) **CLAIM**

We claim the ornamental designs for a in line pump throat, as shown.

DESCRIPTION

FIG. 1 is an elevational view of an in line pump throat showing my new design;

FIG. 2 is a rear elevational view;

FIG. 3 is a front elevational view;

FIG. 4 is an elevational view of an in line pump throat showing a second embodiment of my new design;

FIG. 5 is a rear elevational view of FIG. 4;

FIG. 6 is a front elevational view of FIG. 4;

FIG. 7 is an elevational view of an in line pump showing a third embodiment of my new design;

FIG. 8 is a rear elevational view of FIG. 7; and,

FIG. 9 is a front elevational view of FIG. 7.
